INSULATOR, PAD, OR THE LIKE FOR
HELMETSHerbert Glencairn Wright Chichester-Miles,
London, EnglandApplication September 3, 1940, Serial No. 355,237
In Great Britain May 31, 1939

3 Claims. (Cl. 2-3)

This invention relates to insulators, pads or the like for helmets and the primary object of the invention is to provide devices formed of resilient material which will act as insulators between the inner portion or lining of the helmet and the outer shell thereof and at the same time assisting in locating the said inner portion in position inside the shell. A further object is to provide devices of such a construction that they can be fitted to the lining quickly and in a simple manner without employing metal or other fastenings.

According to this invention, the insulator pad or the like is of resilient material and comprises a body portion having a stud or projection extending from its one face which stud is formed so as to be retained in a slot in a band or like portion of a lining.

The invention is particularly applicable to the insulators which are secured to the lining within the helmet and which serve to locate same within the shell and according to this invention each insulator comprises a base portion of resilient material having a pad-like projection or head on its one face, and a stud or projection extending from its other face, the said stud being formed so as to engage and be retained in a slot in a band of the lining.

For example, the said stud of each insulator comprises a resilient flat undercut member, the terminal portion thereof being of a size slightly greater than the slot so that the terminal portion will pass through the slot and retain the insulator firmly in position.

The invention may also be said to comprise a lining for use in a crash helmet, said lining comprising a head surrounding band and two cross-over head bands, the said bands being provided with a plurality of spaced apart elongated apertures, and a plurality of insulators of resilient material, each said insulator consisting of a body portion having a head or projection from its one face towards its one end, and a stud, one said insulator being fitted and retained on the band by passing its stud through one of the said apertures.

In order that a clear understanding of the invention may be obtained reference will now be made to the accompanying sheet of drawings, wherein:

Figure 1 is a fragmentary perspective view of a lining for use in a protective helmet having preferred forms of insulators constructed in accordance with this invention attached thereto,

Figures 2, 3 and 4 are side, end and plan views respectively of one preferred form of stud for at-

5 attachment to the band of the lining adapted to fit round the head, and

Figure 5 is a plan view of a preferred form of stud for attachment to the band of the lining adapted to fit over the head.

Referring to the drawing, the lining is of conventional form and includes what may be termed a surrounding head band 1, and two cross-over head bands, one of which, 2, is shown.

10 The insulator comprises a substantially rectangular strip like base portion 3, said base portion having a head 4 which projects from its one or outer face at one end. Upstanding from the other or inner face is an elongated stud-like member, comprising a shank portion 5 and a flat enlarged terminal portion 6. In the example illustrated in Figures 2, 3 and 4, the stud like member is mounted with its longitudinal axis transversely of the longitudinal axis of the base portion 3 of the insulator, while in Figure 5 the stud member is mounted with its longitudinal axis on the same line as the longitudinal axis of the base portion 3.

15 The head band 1 is provided with a plurality of four spaced apart elongated apertures 7, and each cross over-head band 2 is provided with a plurality of two similar apertures, one near each end, each for the reception of the stud of one insulator. The slots of the band 1 are longitudinally disposed therein while the slots of the band 2 are transversely disposed.

20 In use, one insulator is retained in each slot by passing the stud thereof through said slot, the insulator being retained in position by virtue of the size of the enlarged terminal portion of the stud thereof and its undercutting. The stud illustrated in Figures 2, 3 and 4 is fitted to the band 1 and the stud illustrated in Figure 5 is fitted to the cross over bands.

25 The heads of the insulators bear against the inside of the steel or like shell when the lining is secured in position within said shell.

The insulators are conveniently moulded in one piece from rubber.

30 I claim:

1. In a helmet insulating lining, a surrounding head band, a cross-over band connecting two opposite points on said head band and adapted to pass over the top of the head, said bands being provided with mounting apertures, a plurality of resilient shock insulator members each comprising a resilient mounting stud formed integrally with said insulator member and projecting therefrom, each said stud comprising a restricted shank portion and further comprising an

enlarged terminal portion conforming in shape to but slightly larger than said mounting apertures for lockingly mounting said insulator member on the outer surfaces of said bands.

2. In a helmet insulating lining, a head band adapted to surround the head and provided with a plurality of elongated mounting apertures extending longitudinally of said head band, a plurality of resilient shock insulator members each comprising a resilient mounting stud formed integrally with said insulator member and projecting therefrom, each said stud comprising a restricted shank portion and an enlarged terminal portion, each said shank portion being relatively flat and elongated and conforming in shape to but being smaller than said mounting apertures for readily passing through said apertures, each said terminal portion being elongated and conforming in shape to but being slightly larger than said mounting apertures, for lockingly mounting said insulator members on the outer surfaces of said band. 20

3. In a helmet insulating lining, a surrounding head band, a cross-over band connecting two opposite points on said head band and adapted to pass over the top of the head, said bands being provided with a plurality of elongated apertures, a plurality of resilient shock insulator members each comprising a resilient mounting stud formed integrally with said insulator member and projecting therefrom, each said stud comprising a restricted shank portion and an enlarged terminal portion, each said shank portion being relatively flat and elongated and conforming in shape to but being smaller than said mounting apertures for readily passing through said apertures, each said terminal portion being elongated and conforming in shape to but being slightly larger than said mounting apertures, for lockingly mounting said insulator members on the outer surface of said bands.
